[57] CLAIM

The ornamental design for a pocket game housing, substantially as shown and described.

DESCRIPTION

FIG. 1 is an oblique view showing the front, the left side and the top of the pocket game housing showing my new design;

FIG. 2 is a rear elevational view thereof;

FIG. 3 is a side elevational view thereof illustrating the side which is not visible from FIG. 1; and

FIG. 4 is a bottom plan view thereof.

FIG. 3

UNITED STATES PATENT AND TRADEMARK OFFICE
CERTIFICATE OF CORRECTION

PATENT NO. : Des. 260,537
DATED : SEPTEMBER 1, 1981
INVENTOR(S) : MASAKI MAYUZUMI

It is certified that error appears in the above-identified patent and that said Letters Patent are hereby corrected as shown below:

On The Title Page:

The title of the patent should read --GAME HOUSING-- instead of "Pocket Game Housing".

Signed and Sealed this

Eighth Day of December 1981
